DESIGN FOR A DRESS

Mollie Stone, New York, N. Y.

Application February 8, 1939, Serial No. 82,855

Term of patent 3½ years

To all whom it may concern:

Be it known that I, Mollie Stone, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design;

Fig. 2 is a rear view thereof;

Fig. 3 is an enlarged fragmentary view of the

dress shown in Fig. 1, illustrating the lace appliqués on the skirt portion in detail.

The characteristic feature of my design resides in the combination on the specific dress disclosed of the specific lace appliqués arranged on the skirt as shown, in association with the matching lace of the collar.

I claim:

The ornamental design for a dress, substantially as shown and described.

MOLLIE STONE.
